Primary Examiner — Austin Murphy*(74) Attorney, Agent, or Firm* — Gottlieb, Rackman & Reisman, P.C.(57) **CLAIM**

The ornamental design for module for a head mounted display, as shown and described.

DESCRIPTION

FIGS. 1-8 illustrate a module for a head mounted display in which FIG. 1 is a front perspective view thereof;

FIG. 2 is front elevation thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a rear perspective view thereof.

The long-short dashed lines represent unclaimed boundaries of the claimed designs. The short dashed lines in the figures are for the purpose of illustrating environmental structure and form no part of the claimed design.
